UNITED STATES PATENT OFFICE

ROBERT B. STEWARD, OF NEW YORK, N. Y.

SHIP'S DAVIT

Application filed April 30, 1929. Serial No. 359,206.

This invention relates to ships' davits and has for its object to provide a combination of elements comprising the davit so constructed and arranged that the boat supported by the davit may be swung to outboard position by the action of gravity by successive swinging movement of pivoted members of the davit construction, and may be swung back into inboard position by reverse movements of said members. Trackways and like obstructions are not employed.

The invention will be described with reference to the accompanying drawings, in which—

15 Figure 1 illustrates an embodiment of the invention in side elevation mounted upon the deck frame of a ship, the davit lying in inboard position, and

20 Figure 2 is a similar view showing the position of the davit outboard;

Figure 3 is a side elevation of opposed davits from inboard position;

25 Figure 4 is a fragmentary view in rear elevation of a joint connecting two of the davit members;

Figure 5 is a similar view showing in dotted lines the position of the parts with the uppermost of said members swung outward to final position, and

30 Figures 6 and 7 are separate views of the members separated.

In the present embodiment the davit comprises a bracket member 1 adapted to be directly connected to the metal deck frame 2.

35 For this purpose the bracket is provided with opposed flanges 3 having apertures for the passageway of bolts 4 connected to 2. The deck covering of the ship is indicated at 5. Pivoted at 6 upon bracket 1 is the lowermost davit member 7. In the present instance the member 7 is formed with the outer leg *a* and the inner leg *ax*.

An intermediate davit member 8 is pivoted 45 at 9 to lower member 7. For this purpose lower member 7 is formed at its upper end with a centrally disposed passageway 10 to receive a lug 11 depending from member 8, as is illustrated more particularly in Figs. 4 to 6 inclusive. Above lug 11 and at each

face thereof davit member 8 is formed with a seat 12 extending in an oblique line relatively to the longitudinal axis of member 8. The upper face of davit member 7 extends in a line horizontal to the axis of said member at 7° and thence angularly at 7^{**} , the degree of the angle being the same as that of faces 12. When the parts are assembled and the davit is inboard, face 7^{**} is in contact with faces 12 and affords a stop against movement of member 8 relative to member 7, except in an outboard direction.

Pivoted upon davit member 8, at 13, is the uppermost davit member 14, said member being curved to generally correspond with the curvature of ships' davits of the usual construction. The form and arrangement of the connection and the contiguous faces of davit members 8 and 14 are the same as those of davit members 7 and 8 and do not require detailed description, the seat at the upper end of davit member 8 being indicated at 14° .

Referring to Fig. 3 I have shown a power driven drum 15 on a shaft 16 which extends to a second drum 17. Drum 15 is connected to a line 18 and line 18 is first led over a guide pulley 19 mounted on bracket 20 of davit member 14, the line then engaging a guide pulley 21 near the top of davit member 14 and thence passing over sheave 22 for connection to the boat 23.

Drum 17 has connected thereto a line 24, led over a guide pulley 25 rotatably mounted on bracket 26 carried by the second of the 85 companion davits, the line thence engaging guide pulley 27 and being led over sheave 28 for connection to boat 23. That portion of the boat opposite either one of the davits lies generally within the dotted lines 29, Fig. 90 1, the boat at its major transverse area being indicated by the full lines in said figure.

In the operation of the embodiment above described, release of the lines 18, 24 will enable action of the davit as follows:—

The gravity pull of the boat upon davit member 14 will cause said member to swing on its pivot 13, carrying the boat outwardly and downwardly to the position A, Fig. 1, the said davit member 14 lying in the posi-

tion A', Fig. 1. In such position the opposed faces lying above the depending lug of member 14 will rest upon the seat 14^x of davit member 8. Continued release of the line will swing davit members 14 and 8 outwardly in unison until they assume the position shown in dotted lines B', Fig. 1, the boat lying in the position B, Fig. 1. At this point faces 12 of davit member 8 will rest upon seat 7^x of davit member 7. Continued release of the line will cause a swinging movement of the lowermost davit member 7 from the position illustrated in Fig. 1 to the position illustrated in Fig. 2, and leg *a* will be brought into engagement with the ship structure, the latter affording a stop against further outboard movement of the davit. The boat has been swung not only outboard but away from the side of the ship.

By means of the invention a very simple combination of elements is employed whereby the weight of the boat is caused to successively swing elements of the davit to outboard position, the boat being automatically swung outboard and lowered. In this operation there is no bodily movement between the lowermost or base davit member and its support, the movement being pivotal. This is an advantage over structures designed to generally achieve the same purpose since the use of trackways is avoided and the restoring of the boat and davit to inboard position requires less power, the elements of the davit acting successively as levers in swinging the boat inboard.

It will be understood that various modifications may be made in the form and arrangement of the elements shown and described without departing from the spirit of the invention, what I claim and desire to secure by Letters Patent being as follows:—

1. In gravity davits for ships, a lowermost davit section having opposed laterally projecting stop members and adapted to be pivotally connected to the ship structure at a point intermediate said stop members, an uppermost davit section, and an intermediate davit section pivotally connecting the lowermost and uppermost sections.

2. In gravity davits for ships, a lowermost davit section having opposed laterally projecting stop members and adapted to be pivotally connected to the ship structure at a point intermediate said stop members, an uppermost davit section, an intermediate davit section pivotally connecting the lowermost and uppermost sections, a pulley carried by the uppermost davit section, and a guiding and fulcrum element carried by the intermediate davit section, the said guiding and fulcrum member being so related to the pulley that a line extended over the two will serve to swing the uppermost davit section at its pivotal connection upon the intermediate section.

3. In gravity davits for ships, a lowermost davit section having opposed laterally projecting stop members and adapted to be pivotally connected to the ship structure at a point intermediate said stop members, an uppermost davit section, an intermediate davit section pivotally connecting the lowermost and uppermost sections, a pulley carried at the end of the uppermost davit section, a bracket carried by the innermost section and a sheave carried by said bracket, as and for the purpose set forth.

4. A gravity davit for ships constructed in accordance with claim 1, in which the pivotal connection intermediate the davit sections comprises a lug at the end of one section, a socket formed in the opposed section and receiving said lug, the overhanging wall at each side of said lug extending diagonally with respect to the longitudinal axis of the davit section on which it is formed and the socketed davit section being formed with angularly related upper faces at each side of the socket affording two seats for the davit section carrying said lug.

5. In gravity davits for ships, a lowermost davit section, an uppermost davit section, and an intermediate davit section pivotally connecting the lowermost and uppermost sections, said davit sections at points of mutual contact being formed with two sets of stop surfaces, the first set mutually engaging when the davit is inboard and the second set mutually engaging when the davit is outboard and opposed legs carried by the lowermost davit section, as and for the purpose set forth.

In testimony whereof, I have signed my name to this specification.

ROBERT BRUCE STEWARD.
